UNITED STATES PATENT OFFICE.

MALCOLM SCOUGALE, OF WEATHERFORD, TEXAS.

PENCIL-SHARPENER.

1,372,562.

Specification of Letters Patent. Patented Mar. 22, 1921.

Application filed June 26, 1920. Serial No. 391,957.

To all whom it may concern:

Be it known that I, MALCOLM SCOUGALE, a citizen of the United States, residing at Weatherford, in the county of Parker and State of Texas, have invented new and useful Improvements in Pencil-Sharpener, of which the following is a specification.

This invention relates to stationery, particularly to pencil sharpeners, and has for its object the provision of a pencil sharpener so constructed as to form a concavity in the end of a pencil lead so as to produce a circular writing edge, all points of which may be used and which will consequently be a distinct improvement over the ordinary point commonly formed by the ordinary pencil sharpener and which so quickly becomes dull.

An important object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings in which—

30 Figure 1 is a side elevation of a pencil sharpener constructed in accordance with my invention,

Fig. 2 is a longitudinal sectional view therethrough,

35 Fig. 3 is an enlarged longitudinal sectional view through the end of a pencil sharpened by means of my device, and

Fig. 4 is a longitudinal section through a modified form.

40 Referring more particularly to the drawings, the letter A designates a pencil and B designates the so-called lead thereof.

In carrying out my invention I provide a sharpener formed as a shell 10 which includes a cylindrical portion 11 and a tapered portion 12. Located within a slot 13 in the tapered portion is a cutting blade 14 which is inclined and which is adapted to shave away the wood part of the pencil and also a portion of the end of the lead. Ordinarily sharpeners of this character form a point at the end of the lead.

The important feature of my invention is the provision of a cutting member operating

55 against the end of the lead for forming a concavity therein, and in actual practice this

may be accomplished in a variety of ways though in the present instance I have shown a screw 15 threaded into the end of the tapered portion 12 of the shell, having a 60 knurled or milled adjusting head 16 and having its point 17 formed with a cutting blade similar to that of a counter-sink.

In sharpening a pencil by means of my device, the operation is the same as that of 65 any other sharpener, it being noted that my device is preferably provided with a handle 18 facilitating its engagement by the operator's fingers. As the pencil is sharpened the end portion of the lead will be shaved 70 away slightly at the sides and at the same time a concavity 19 will be formed in the end of the lead. As shown in the drawings, this concavity is conical though it is readily apparent that it might be cylindrical or 75 merely dished if desired, the shape making no difference as the object is to form the circular sharp edges 20, all points of which may be used for writing. It will be observed that this sharp edge will last much 80 longer than a simple point which is ordinarily formed and it will be noted that my device is consequently a distinct step forward.

Referring more particularly to the form 85 shown in Fig. 4, it will be seen that my invention is capable of wide variation in the details of construction. In this form I employ a shell 21 which may be purely cylindrical or which may have a tapered portion, 90 as preferred, and formed either with or without a handle. Located within one end of this shell is a sharpening member 22 which in actual practice I form from Portland cement and ground glass. This member is so shaped that when a lead pencil, which may have had its wood portion shaved down by any means, is inserted within the shell and rotated, the member 22 will operate to form a concavity in the end of the so-called lead.

While I have shown and described the preferred embodiment of my invention, it is of course to be understood that I reserve the right to make such changes in the form, 105 construction, and arrangement of parts as will not depart from the spirit of the invention or the scope of the subjoined claims.

Having thus described my invention, I claim:

1. A device of the character described comprising a shell including a cylindrical

- portion and a tapered portion, the tapered portion being provided with a slot, an inclined blade located within the slot and projecting inwardly of the inner periphery of the tapered portion, a handle on said shell, and a cutting member located at the apex of the tapered portion and adapted to produce a concavity in the end of the lead of a pencil engaged within the device.
- 10 2. A device of the character described comprising a shell including a cylindrical portion and a tapered portion, the tapered portion being provided with a slot, an inclined blade located within the slot and projecting inwardly of the inner periphery of the tapered portion, a handle on said shell, and a cutting member located at the apex of the tapered portion and adapted to produce a concavity in the end of the lead of a pencil engaged within the device, said cutting member being adjustable whereby to extend a greater or less extent into the shell.
- 15 3. A device of the character described comprising a shell including a cylindrical portion and a tapered portion, the tapered portion being provided with a slot, an inclined blade located within the slot and projecting inwardly of the inner periphery of

the tapered portion, a handle on said shell, and a cutting member located at the apex of the tapered portion and adapted to produce a concavity in the end of the lead of a pencil engaged within the device, said cutting member being adjustable whereby to extend a greater or less extent into the shell and being formed as a screw threaded into the shell and having its point formed with a plurality of radial cutting edges.

4. A device of the character described comprising a shell adapted to receive the sharpened end of a pencil, and means within said shell for forming a concavity in the end of the pencil "lead."

5. A device of the character described comprising a shell adapted to receive the sharpened end of a pencil, and a cutting member within said shell adapted to form a concavity in the end of the pencil "lead."

6. A device of the character described comprising a tapered shell adapted to receive the end of a pencil, and a cutting member at the apex of said shell engageable by the end of the pencil "lead" whereby to form a concavity therein.

In testimony whereof I affix my signature.

MALCOLM SCOUGALE.
